UNITED STATES PATENT OFFICE.

WILLIAM STEVENS, OF RICHMOND, INDIANA, ASSIGNOR TO THE GAAR,
SCOTT & COMPANY, OF SAME PLACE.

DESIGN FOR A TOOTH FOR CYLINDERS AND CONCAVES OF THRESHING-MACHINES.

SPECIFICATION forming part of Design No. 28,543, dated May 3, 1898.

Application filed January 31, 1898. Serial No. 668,679. Term of patent 14 years.

To all whom it may concern:

Be it known that I, WILLIAM STEVENS, a citizen of the United States, and a resident of the city of Richmond, in the State of Indiana, have invented a new and original De-

5 sign for the Teeth of the Cylinders and Concaves of Threshing-Machines, of which the following is a specification, reference being had to the accompanying drawings, in which—

10 Figure 1 is a perspective view of the tooth. Fig. 2 is a sectional view on line 2 2, Fig. 1.

In the drawings, A is the flat body portion of the tooth, and B C is the shank. The part B of the shank is cylindrical. The part C 15 of the shank, which intervenes between the parts B and A, is square or rectangular in

cross-section and is set so that its flat longitudinal faces c are diagonal or quartering to the flat broader faces a of the body A, this constituting the essential feature of my de- 20 sign.

What I claim, and desire to secure by Letters Patent, is—

The design for a tooth for the cylinders and concaves of threshing - machines, substan- 25 tially as shown.

In testimony whereof I have hereunto set my hand this 24th day of January, 1898.

WILLIAM STEVENS.
